UNITED STATES PATENT OFFICE.

HUGO PISCHON AND RICHARD PFENNIG, OF BERLIN, GERMANY, ASSIGNORS
TO THE INTERNATIONALER VAKUUM EIS-MASCHINEN VEREIN, OF SAME
PLACE.

VACUUM ICE-MAKING MACHINE.

SPECIFICATION forming part of Letters Patent No. 350,270, dated October 5, 1886.

Application filed July 10, 1886. Serial No. 207,638. (No model.) Patented in France September 17, 1885, No. 171,219; in Germany October 17, 1885, No. 36,055, and in Austria-Hungary March 21, 1886, No. 42,420 and No. 7,025.

To all whom it may concern:

Be it known that we, HUGO PISCHON and RICHARD PFENNIG, both residents of the city of Berlin, in the Kingdom of Prussia, and German Empire, have invented certain Improvements in Vacuum Ice-Making Machines, (for which Letters Patent have also been obtained in Germany under the No. 36,055, dated the 17th of October, 1885; in France under the No. 171,219, dated the 17th of September, 1885, and in Austria - Hungary under the No. 42,420 / 85—Tom. 36, fol. 490, dated the 7,025 / 86—Tom. XX, fol. 501, 26th of March, 1886,) of which improvements the following is a specification.

Our invention relates to a machine for making ice and for cooling fluids, and requiring such little working power that it can be driven by hand, if necessary.

20 The machine is represented in the accompanying drawings.

Figure I shows a longitudinal section, and Fig. II a front view of it, and Fig. III shows a modification of the construction for the absorber.

25 The machine is based in its construction on the well-known physical principle of the evaporation of water in spaces containing rarefied air, and the parts of the machine are materially as follows: first, the ice-generator and water-cooling apparatus E; second, the absorber A; third, the evaporator (concentrator) C'; fourth, the vacuum-pump with two air-cylinders, P and P', which are placed on both sides of a pillar-shaped frame, S'; and, fifth, the driving mechanisms appertaining to the machine, and, finally, the tubes connecting the above-mentioned parts.

30 The ice-generator or water-cooling apparatus E consists of a hollow glass cylinder, E', the end surfaces of which are ground straight. The glass cylinder E is pressed by means of a screw mechanism between the two india-rubber rings K K', with which the two cast-iron lids G and H are provided. The upper lid, G, is firmly connected with the waste-pipe S, and is bent in the shape of a bow, whereas the lower lid, H, which is shaped like a table, can be moved up and down by means of screw and hand-

wheel M. This lid is prevented from turning by a shoulder, D, working in a groove of the waste-pipe S, which forms at the same time the frame of the machine.

50 The ice-generator stands in connection with the absorber A by means of the waste-pipe S, which allows the water-vapors to escape. The absorber A consists of a cylinder mounted vertically or horizontally, which cylinder is either of a common form, as shown in Fig. II, or of a longitudinally-undulatory shape, as shown in Fig. III. This cylinder may be made either of cast or wrought iron or of hard lead. The absorber is filled in part with sulphuric acid or any other fluid that absorbs water-vapors, and has in its center axis a rotating peculiarly-shaped stirring apparatus, the ends of which rest in bushes. The stirring apparatus is fastened to the axle R, and is driven by cog-wheels or friction-plates and by the vertical axle T direct from the main shaft B. Two kinds of stirrers are fastened to the axle R. 65

60 The one sort consists of the perforated plates Y, bent undulatorily, whereas the other sort is composed of scoops X, standing inclined toward the axle R and placed between the plates 70 just named. The object of the scoops X is to effect a very close mixture, and to scatter the absorbing-fluid, whereas the stirring-plates Y are intended to make a wetted upper surface as large as possible and above the level of 75 the fluid, for the water-vapors that have to be absorbed are forced to pass through the perforations and the open circuit surfaces of the stirring-plates Y. The front lid of the absorber A gradually develops into a hollow vertical cast-iron pillar, N, the closed lower part of which forms the dome of the absorber. In the lower swelling of this lid are the wheel-works Z' Z'' for the stirring apparatus. The vertical shaft T, which transmits the motion from the 80 main shaft B onto the axle R, and which is packed in a stuffing-box, V, has underneath the latter and inside the dome a shade, W, which serves to prevent any particles of the absorbing-fluid that may be dashed upward from getting 85 at the mouth of the tube and the stuffing-box. When only small quantities of ice have to be 90 made, it suffices in the most cases to let the acid

which has got heated by absorbing the water-vapors, cool by the effect of the outer air on it, and the simplest way of obtaining a large cooling-surface for this purpose is to use the jacketed surface of the absorber-cylinder as it is represented in undulatory shape in Fig. III. A more energetic cooling of the acid is arrived at by enveloping the absorber loosely with a blanket, and by pouring water (or any other fluid) on this blanket. The water thus poured on evaporates, and by abstracting heat from the cylinder helps to cool it.

The concentrator serves to evaporate the water absorbed by the sulphuric acid. It consists of a hard-lead pan, C', open at the top and filled with sulphuric acid used before to absorb the water-vapors, and is suspended in a larger copper or iron vessel, Q. The intermediate space between C' and Q thus formed is filled with a fluid hard to boil—for instance, caustic soda, glycerine, &c. This fluid is selected with due regard to the fact that its boiling-point is higher than that of the sulphuric acid to be concentrated, while, on the other hand, its boiling-point is lower than the melting-point of the lead of which the evaporation-pan is made. In order to prevent the temperature of this fluid from getting above the degree of concentration of the sulphuric acid and above its own boiling-point, when heated from outside by a gas or petroleum flame or by a coal fire, the hollow space mentioned above is connected with an upper-surface condenser, T, by means of a tube, L. Cooling-water is continually flowing through the condenser, and therefore whenever vapors are formed by over-great heat they are led into the condenser, are condensed in it, and are then conducted back in the shape of water to the heated hollow space through tube L'. In using this fluid bath the object in view is to obtain such a boiling temperature as is necessary for the evaporation of the sulphuric acid and to keep up this temperature continually.

The pumps P and P' serve to form the vacuum in the absorber and the ice-generator. The suction-pipe N' of the large air-rarefying pump P is in connection with the support N of the absorber. The pump P sucks up the air out of the absorber and forwards it to the second small pump, P', which compresses the air to the atmospheric tension and ejects it. By means of this simple combination a high vacuum is obtained in a very simple manner. The two pumps are driven from the shaft B, which rotates in two bushes on the pillar-frame S', and has at one end a crank, U', for driving the large pump P, at the other end an eccentric, U², for driving the smaller pump, P', and has behind the eccentric a fly-wheel, U³, with a winch-handle, U, for working the whole machine.

The way in which this hand ice-making machine is worked is as follows: When the necessary vacuum has been formed in the hermetically-closed space E, the water that has to be congealed is sucked up out of a water-

vessel, Z, placed ready for use, and flows through pipe q' and the cock q, which is provided with a scale and indicator, and is set exactly for showing the quantity of the inflowing water. As soon as the water enters the almost airless space, the congealing process begins immediately, for the water commences to boil most actively, and as a small portion of it evaporates so much warmth is extracted from the remaining part that it freezes and becomes ice. When the necessary quantity of ice has been made, which can be easily observed through the glass vessel E' from outside, valve V' (connecting the space E with the absorber A) is shut off, air is admitted through cock q, and by lowering the under lid, H, the block of ice can be removed from the glass cylinder E'. If water or any other fluid has to be cooled, so much water (or other fluid) is allowed to run through cock q into the airless hollow space of the cylinder E' that an active evaporation of the water or fluid takes place, but not so much as to allow the temperature to sink below the temperature that is wanted. In this manner water can be cooled down to the freezing-point, and fluids hard to freeze can be brought to a temperature some degrees below that point even. Air is admitted into the glass cylinder and the cooled water runs out through cock O.

Having thus described our invention, and also the manner how and the means with which it is to be performed, what we claim, and desire to get secured by Letters Patent of the United States, is—

1. In a machine for making ice and for cooling fluids, the combination of a vertically or horizontally placed absorber, A, with the two-chamber vacuum-pump P P', firmly connected with the absorber, the ice-generator E, with its glass vessel E', and with a concentrator, C, for the evaporation of the diluted sulphuric acid, substantially as described, and for the purpose as set forth.

2. In an ice-making machine, the ice-generator E, consisting of the table or under lid, H, adjustable by means of a screw, M, and of the hollow glass cylinder E', in combination with valve V, waste-pipe S, and absorber A, substantially as specified.

3. In an ice-making machine, the combination of absorber A with the stirring apparatus consisting of shaft R, undulatory perforated stirring-plates Y, and intermediate wings or scoops, X, set in an inclined position to the common axle, and means for operating said axle, substantially as and for the purpose described.

4. In an ice-making machine, the longitudinally-undulatory absorbing-cylinder A, in combination with stirring apparatus Y X, shaft R, gearing Z Z', shaft T, gear-wheels Z³ Z⁴, and shaft B, substantially as described.

5. In an ice-making machine, the combination of the pan C', for evaporating the received diluted sulphuric acid with the outer vessel, Q, containing a fluid bath the boil-

ing-point of which is higher than that of the sulphuric acid to be concentrated and lower than the melting-point of the pan C', substantially as and for the purpose specified.

5 6. In an ice-making machine, the arrangement for maintaining a constant temperature of the fluid in the concentrator and for condensing and reconducting all vapors that may develop by the fluid bath.

10 7. The combination of the pan C' and ex-

ternal vessel, Q, with the tubes L L' and surface-condenser J, substantially as specified.

In testimony whereof we have signed our names to this specification in the presence of two subscribing witnesses.
